BOLT-RETAINER FOR PRECASTING IN CONCRETE

Roland G. Nasser, Newburgh, N.Y., assignor to Star Expansion Industries, Corporation, Mountainville, N.Y.

Filed Apr. 17, 1972, Ser. No. 245,013

Term of patent 14 years

Int. Cl. D8—08

U.S. Cl. D8—228

FIG. 1.

FIG. 2.

FIG. 3.

FIG. 4.

FIG. 5.

FIG. 1 is a perspective view of a bolt-retainer for pre-casting in concrete showing my new design;

FIG. 2 is a top plan view thereof, the bottom being substantially identical therewith;

FIG. 3 is a front elevational view thereof;

FIG. 4 is a side elevational view thereof, the opposite side thereof being generally identical therewith; and

FIG. 5 is a rear elevational view thereof.

I claim:

The ornamental design for a bolt-retainer for pre-casting in concrete, substantially as shown and described.
